CLAIM

The ornamental design for a storage box, as shown and described.

DESCRIPTION

FIG. 1 is a perspective view of a storage box showing the new design;

FIG. 2 is a perspective view of the storage box with its top tray disconnected;

FIG. 3 is another perspective view thereof;

FIG. 4 is top plan view of the storage box with its top tray connected;

FIG. 5 is a bottom view thereof;

FIG. 6 is a front elevation view thereof;

FIG. 7 is a rear elevation view thereof;

FIG. 8 is a left side elevation view thereof;

FIG. 9 is a right side elevation view thereof; and,

FIG. 10 is a front elevation view of the storage box with its top tray disconnected.

The equal length broken lines depict portions of the storage box that form no part of the claimed design.

1 Claim, 10 Drawing Sheets
